UNITED STATES PATENT OFFICE.

JOSEPH JAMES PATCHETT, OF HALIFAX, ENGLAND, ASSIGNOR TO JOSEPH WILD & CO., OF NEW YORK, N. Y.

DESIGN FOR A CARPET-PATTERN.

Specification forming part of Design No. 6,007, dated July 23, 1872.

Specification describing a new and original Design for a Carpet, invented by JOSEPH J. PATCHETT, of Halifax, in the county of York, England.

The accompanying photographic illustration fully represents my new design.

This invention relates to a new carpet-design, in which two main figures of very fantastic outline are employed. One-half of each figure is represented in the photograph. That one of the two figures which has the square

in the center is contained in a border having a partly-straight and partly-curved outline, and rounded at the corners. The other figure, having an oval center, has a scroll outline, as shown.

I claim as my invention—

The design for a carpet, as shown.

JOSEPH JAMES PATCHETT.
